[57] CLAIM

The ornamental design for an insulating member for
livestock-enclosure fences, substantially as shown and
described.

DESCRIPTION

FIG. 1 is a front elevational view of an insulating mem-
ber for livestock-enclosure fences showing my new
design;

FIG. 2 is a left side elevational view thereof, the side
opposite being a mirror image;

FIG. 3 is a rear elevational view thereof; and

FIG. 4 is a left side and front perspective view thereof.
